H. DENNIS

SURGICAL SAW

Filed March 1, 1924

Inventor

Hugh Dennis

By his Attorney

James G. Campbell

UNITED STATES PATENT OFFICE.

HUGH DENNIS, OF NEW YORK, N. Y., ASSIGNOR TO THE KNY-SCHEERER CORPORATION OF AMERICA, OF NEW YORK, N. Y., A CORPORATION OF NEW YORK.

SURGICAL SAW.

Application filed March 1, 1924. Serial No. 696,145.

My invention relates to an improvement in surgical saws of the rotary motor operated type and its novelty consists in the adaptation and arrangement of parts as will be 5 more fully hereinafter pointed out.

There has been great difficulty in making deep incisions in bone operations as most of the devices available are not adapted for that purpose. My device not only is capable 10 of making any necessary incision but at the same time has furnished a device adapted to be used for drilling operations which are often necessary in bone operating so that the interchangeability of the device is important 15 in saving valuable time in the course of such operations.

My device also is readily sterilized and meets all of the requirements essential to successful bone operations.

20 Referring to the drawings Figure 1 is a perspective of my complete device without the power connections. Figure 2 is a side view of the arm carrying the transmission of the saw and is broken away at the shaft 25 end to show the interior mechanism. Figure 3 is a vertical section of the outer end of the shell and shaft connecting up with the motor. Figure 4 shows one type of 30 single saw mounted in position for use, the rest of the arm being broken away for convenience in illustration. Figure 5 shows another type of single saw mounted in position for use with the arm broken away as in 35 Figure 4. Figure 6 is a side view of twin saws with parts of the saws and connections being broken away as in Figure 4. Figure 7 is a plan view of the shaft, the inside end being broken away for convenience in illustration.

40 In the drawings shell members 8 and 10 are locked together at 9 and contain an electric motor of the usual type used in instruments of this class. In the head of the shell 10 is a connecting member 11, being internally threaded at 13, whereby it is adapted to be secured to the motor which is not shown herein. The outer end of said connecting member 11 is also internally threaded at 45 so as to receive a bearing member 12 which is externally threaded so as to engage the internal threading 45 of 11. A lock nut 46 is adapted to be threaded over 45 so as to lock shell 10, connecting member 11 and bearing member 12 together. The connect-

ing member 11 has a dividing wall 14 having a central opening 15. Spacing member 16 having a cutout portion 17 is adapted to receive one race of ball bearing 18 and a second cutout portion 19 in the dividing plate 15 is adapted to receive the other race of 55 said ball bearing 18. A cylindrical shaft 20 is adapted to be mounted in the bearing member 12 and it has a reduced inner cylindrical end 21 one-half of which is cut off so as to engage a similar semi-cylindrical end of the motor shaft which is not shown, which semi-cylindrical members lock so as to transmit the motion of the motor to the shaft 20 and they run on the ball bearing 18. The bearing member 12 has 60 a slot 22 and in alignment with slot 22 the shaft 20 has a gear 23 cut therein. An arm 24 composed of two complementary grooved plates secured together and having a collar 25 is adapted to be mounted on the bearing 65 member 12 by means of set screw 26. The arm 24 also has a movable gear shifting member 27 pivoted at 28 and carrying a gear 29 on a pinion 30. The shifting member 27 is secured in position by means of a 70 thumb screw 31 and as this is released the carrying member 27 may be dropped into the lower position as shown in dotted outline in Figure 2, thereby lowering the gear 29 from mesh with gear 23. A gear 32 is 75 mounted on the pivot or trunnion 28 and a series of gears the same as 32 are similarly mounted on trunnions the length of the arm 24 so that the gear at the outer end of said 80 arm 24 mounted on shaft 33 will drive said 85 shaft 33 whenever the gear 29 is in position to mesh driving gear 23 and driven gears 32 and the chain of gears inside arm 24 in mesh with said gear 32. A saw 34 is adapted 90 to be rigidly secured to the shaft 33, which 95 is threaded, by means of circular nut members 35 which are adapted to be screwed up tightly on either side of said saw 34. The shaft 33 is adapted to be mounted at one end in the plate 43 and at the other end is 100 adapted to be mounted in a bearing in an offset member 36, which is adapted to be rigidly secured to the plate 44 at 37. The particular form of 36 will vary according to the 105 particular saw to be used as is shown in Figures 4, 5 and 6. In Figure 6 the saws are twin saws 38 and 39 and are mounted in a similar manner as saws 34, on the shaft 33.

In Figure 5 the saw 40 is a larger single saw and is mounted on the shaft 33 in the same way as saw 34.

In operating my device the gear 29 will be secured in position as shown in Figure 1 in mesh with the gear 23 and as the power is turned on the shaft 20 and gear 23 will be driven thereby and their motion will be transmitted to gear 29, thence to gear 32 and to the chain of gears in arm 24 to the shaft 33 whereby the saw 34 will be rotated. The particular saw desired may be secured in position before this is done as the operator will know what type of saw will be needed for the operation. If during the operation it becomes necessary to do some drilling the power having been shut off the thumb screw 31 will be released and the gear 29 will be dropped down out of engagement with gear 23 and any drill or similar instrument may be secured in position at 41 and the power again turned on and the drilling operation completed, whereupon the power being turned off the drill may be removed and the gear 29 again returned to its position of engagement with gears 23 and 32 whereupon the saw 34 will then again be set into rotation by the turning on of the power. During the use of the drill the arm 24 will serve as a handle for the operator thereby facilitating his work and making the same more accurate.

The arm 24 may be removed at any time by first throwing the gear 29 out of engagement with gears 23 and 32 and releasing the thumb screw 26 whereupon the arm 24 can be slipped over the bearing member 12 so that the device may be used for boring or similar purposes free from the arm 24.

It is thus seen that my device is so constructed that during the operation the operator can quickly and readily turn from the use of the saw to the use of the drill and back again to the use of the saw without changing instruments whereby a material amount of time may be saved in the operation and the operator's attention be centered upon the one device and the patient.

I claim:

1. In a surgical saw the combination of an electric motor, a detachable shaft adapted to lock into the shaft of said motor and having means for mounting tools therein, a gear cut into said detachable shaft, a bearing member mounted on said shaft, an arm mounted on said bearing member and carrying a saw and a train of transmission gears adapted

to transmit the motion from said shaft to said saw, a shift gear mounted in said arm and adapted to transmit motion from said gear on the shaft to said train of gears in the arm when in meshed position.

2. In a surgical saw the combination of an electric motor, a detachable shaft adapted to lock into the shaft of said motor and having means for mounting tools therein, means comprising a train of gears for transferring the motion of said shafts to a rotary saw, and means for interrupting said transfer of motion to said train of gears.

3. In a surgical saw the combination of an electric motor, a detachable shaft adapted to lock into the shaft of said motor and having means for mounting tools therein, means for transferring the motion of said motor to a rotary saw, and means for interrupting said transfer of motion comprising an intermediate gear adapted to mesh with a gear on said detachable shaft with a train of gears transmitting said motion to said saw and means for throwing said intermediate gear out of mesh.

4. In a surgical saw the combination of an electric motor, a detachable shaft adapted to lock into the shaft of said motor and having means for mounting tools therein, means for transferring the motion of said motor to a rotary saw, and means for interrupting said transfer of motion comprising an intermediate gear adapted to mesh with a gear on said detachable shaft with a train of gears transmitting said motion to said saw and means for throwing said intermediate gear out of mesh embodying a pivoted support member on which said intermediate gear is mounted.

5. The combination with a motor and its shaft of a separable shaft having a tool holder at its outer end adapted to lock with said motor shaft and carrying a gear cut therein, a bearing member mounted over said separable shaft, an arm adapted to be rigidly secured to said bearing member, a rotary saw mounted on a plate in the outer end of said arm, a train of gears mounted in said arm on trunnions the outer one being geared to said saw and a gear pinioned to a pivoted shift member in said arm so that it can manually be thrown into or out of mesh with said shaft gear and said train of gears.

In testimony whereof I affix my signature.

HUGH DENNIS.
